PHARMACEUTICAL APPARATUS

Herman Leffert and Edward E. Woldman, Cleveland, Ohio, assignors, by mesne assignments, to Alba Pharmaceutical Company, Inc., New York, N. Y., a corporation of New York

Application January 31, 1936, Serial No. 61,783

10 Claims. (Cl. 128—225)

This invention relates to a method and apparatus for introducing material into a patient or for removing material therefrom. As applied to a dispensing or introduction of material, the method and apparatus may be used, for example, in the treatment of stomach ulcers where it is desirable to introduce medication continuously in predetermined measured quantities and without interfering with the normal introduction of food into the patient.

We have found that very favorable results in the treatment of ulcers have been obtained by the continuous introduction of medicine into the stomach of a patient at regular intervals. It is impractical to introduce the medicine through the oral cavity at such intervals as are necessary to accomplish the desired results, and so we have devised an apparatus by means of which medication can be accomplished independently of the will or actions of the patient, and at any desired rate of flow.

An object of our invention, therefore, is to provide an apparatus, which will not only be suitable for controlling the rate of flow for stomach medication purposes, but which may likewise be adapted for rectal feeding or medication. In this connection, our invention contemplates an arrangement by means of which the dispensing of the material is maintained at a uniform rate regardless of the level of the material in a reservoir.

A device which has been used for rectal feeding has been so designed that the medicine drops into a long tube which extends from the reservoir into the patient. The difficulty has been that the tube could not be maintained in a position where-in the medicine could flow uninterrupted, as any movement of the bed clothing would be apt to create a looped or sagged portion in which the medicine could collect and subsequently be discharged in large quantities into the patient. Our apparatus maintains the tube filled at all times and allows the medicine to drop only from the end thereof. Consequently there is no danger of discharging an excessive quantity into the patient at any time.

A further advantage of our apparatus is the fact that it may be operated in such manner as to create a suction within the stomach of a patient, so as to permit the removal of gases or liquid matter in post-operative treatment. At present there is an apparatus for withdrawing the stomach contents, but such apparatus requires the extracted material to be mixed with water or other liquid that is used to create the suction. In our apparatus, the extracted material can be collected in

a flask without mixing with any liquid that is utilized for producing the suction.

Referring now to the drawing, Fig. 1 shows one form of apparatus for carrying out our invention; Fig. 2 shows a modified form of the apparatus, while Fig. 3 is a diagrammatic view illustrating the operation of the apparatus shown in Fig. 2 for withdrawing gas from the stomach of a patient.

When the apparatus is used, either for medication or for feeding purposes, it is supported above the level of the patient who usually is in a reclining position. In case it is used for stomach medication, a stomach tube is first inserted through the nostril and past the esophagus, thereby leaving the oral cavity unobstructed for normal use in the consumption of food. In the illustration shown in Fig. 1, the apparatus is supported on a table beside the bed and above the level of the patient's stomach. In such illustration, the stomach tube is indicated, at 10, as having its outer end adapted to be connected, as at 11, to a dispensing tube 12. The tube 12 is shown as extending into a medicine flask 13, and as terminating short of the bottom thereof.

An intermediate, or air flask 14 is disposed beside the medicine flask and is connected thereto by a tube 15. The ends of the tube 15 terminate inside the flasks and adjacent the inner faces of the stoppers 16 and 17 respectively. The flask 14 is empty at the start of the dispensing operation, but is adapted to receive a liquid, such as water, which enters through a tube 20 from a reservoir 21, a valve 22 being used for controlling the rate of flow.

At the start of the dispensing operation the medicine is placed in the flask 13 and the container 21 is filled with liquid, such as water. The various connections shown are then sealed, where-upon the valve 22 in the conduit 20 and the valve 23 in the discharge tube are opened. Water there-upon flows from the reservoir 21 into the flask 14, thus forcing air through the tube 15 into the flask 13, and building up pressure therein. As the pressure increases, medicine is forced into the discharge tube, and thence into the stomach tube. As soon as the medicine rises in the discharge tube, and starts to flow into the stomach tube, a syphoning action commences, and continues until a partial vacuum is created in the flasks 13 and 14. Equilibrium is then established, so that there-after, the medicine flows through the discharge tube at exactly the same rate at which water enters the flask 14. By adjusting the valve 22, any desired number of drops per minute will enter

the flask 14, and the corresponding volume of liquid will be dispensed from the flask 13. If desired, the discharge tube may be temporarily disconnected from the stomach tube during the 5 syphoning action, so as to prevent the flow of an excess quantity of medicine into the patient, but as soon as the medicine flows at the same rate at which water enters the flask 14, the discharge tube is connected to the stomach tube. Such disconnection is not necessary in all cases, for if medicine used is not harmful, the delivery of an excess quantity for a very short period of time 10 will not be objectionable.

As soon as the level of medicine in the flask 13 15 drops below the entrance in the discharge tube, then the valve 22 is closed, the reservoir 21 and the flask 13 are refilled and the flask 14 is emptied. Ordinarily, the flask 13 holds a sufficient quantity of medicine for permitting medication for 20 a period of twenty-four hours.

To minimize the number of connections and thereby to avoid the possibility of air leakage into the vacuum line, and at the same time to eliminate the necessity of utilizing a fluid under 25 pressure to start the flow of material into the dispensing tube, we have shown a modification of our invention which is illustrated in Fig. 2. In such modification, the material to be dispensed is placed in a container 30 which has a discharge 30 tube 31 leading from the bottom thereof.

A valve 23 in the discharge tube prevents the flow of material therefrom until the apparatus is in condition for operation. The flask 30 has a stopper 25 into which a tube 32 extends. The 35 flask end of the tube terminates above the level of the material in the flask while the opposite end of the tube is in communication with an air tight chamber 33. The chamber or compartment 33 may be formed within a container 34 which has another compartment 35 in which water or other 40 liquid can be held. A gas and liquid tight partition 36 separates the two compartments. The container 34 is illustrated as supporting a container 37 which is likewise adapted to hold water, 45 and which is provided with a discharge opening 38 in the bottom thereof. A float controlled valve 40 is carried by the container 37, and is adapted to control the flow of water through the opening 38 from the tank 37 into the tank 34, the 50 adjustment being such that the level in the tank 34 is maintained at the same position at all times.

At the start of the operation, the compartment 33 is empty, and the valve 41 in the drain 55 conduit 42 is closed. Accordingly, as soon as the stomach tube is connected to the discharge tube 31, the valve 23 is opened, and the material in the flask 30 starts to flow and to rarify the air in the compartment 33. As soon as the air is 60 rarified to the point where it will support the head of material in the flask, the flow ceases, and thereafter, it is allowed to continue only in accordance with the rate at which air in the compartment 33 is displaced. Such displacement occurs by allowing water to flow from the 65 compartment 35 into the compartment 33 through a by-pass 45 that is controlled by a valve 46. A portion of the by-pass comprises a glass tube by means of which the number of drops per 70 minute can be observed. The rate of flow from the compartment 35 to the compartment 33 is therefore, the identical rate at which material is allowed to flow from the flask 30.

As soon as liquid flows from the compartment 75 35, the float controlled valve 40 allows the same

amount to drop from the container 37 into the compartment 34. In this way, there is a constant head in the compartment 35 as a result of which the adjustment of the valve 46 maintains a uniform low rate at all times. 5

As soon as the material in the flask 30 is discharged, the flask may be refilled, the compartment 33 drained, and the container 37 refilled. In practice, the container 37 is arranged to hold a larger quantity of liquid than the flask 30 so that there is ample liquid in reserve to assure a discharge of the entire contents of the flask.

There is a slight difference in the operation of the apparatus illustrated in Fig. 1 from that illustrated in Fig. 2 in that no syphoning action 15 in the apparatus of Fig. 2 occurs at the time the dispensing operation is initiated. Furthermore, there are less connections in which air leaks may occur. 20

While we have explained our invention in connection with stomach medication, it is apparent that the apparatus may be used for rectal feeding, in which case the stomach tube is replaced by a rectal tube. The apparatus is likewise well adapted for use as a suction pump to remove gas and liquid material from the stomach in post-operative treatment. To use the apparatus for the latter purpose, it is only necessary to connect it as shown in Fig. 3 and to have the flask 30 empty and the compartment 33 filled with water. 25 The valve 46 is closed, the valve 32 is fully opened, and then the valve 41 is adjusted so as to allow liquid to drain from the compartment 33 at the desired rate. As the level of liquid in the compartment 33 drops, gas or liquid contents are 30 drawn into the flask 30 to replace the liquid which is drained from the compartment 33. 35

While we have shown in each modification an apparatus wherein a partial vacuum is utilized for restraining the rate of flow, and have illustrated 40 apparatus by means of which the volume of air in the reservoir space above the liquid is automatically varied so as to assure a continuous flow at a uniform rate, nevertheless we may, if desired, eliminate the water reservoir, as well as 45 the intermediate compartment into which the water is allowed to drip, and vent the vacuum space by means of the valve 46. The valve may be adjusted so as to bleed into the vacuum space a very small quantity of air which acts as a vent 50 to allow the liquid to flow out of the container. The valve may be opened to any desired degree so as to regulate the rate of flow.

An important advantage of our invention is the fact that material may be introduced into a 55 patient automatically at a constant predetermined rate. This is valuable in the treatment of stomach ulcers, as it permits medication without interfering with the normal introduction of food through the oral cavity. The apparatus is quite 60 simple in arrangement and compact in size and is capable of being readily cleaned and sterilized for repeated use.

We claim:

1. In combination, a container for storing material in liquid form, a discharge conduit leading therefrom, a vacuum chamber in communication with the container above the level of liquid therein, means for introducing a liquid into the chamber to displace the space occupied by a 70 quantity of air therein, and a valve for controlling the rate of flow into the chamber whereby liquid from the container will be proportionately released. 75

2. In combination, a container for liquid, a 7

discharge tube leading therefrom, a valve for controlling the flow through the discharge tube, a vacuum chamber, a tube connecting the vacuum chamber to the space above the liquid in the container, a liquid reservoir, a conduit connecting the reservoir to the vacuum chamber so that liquid may flow from the reservoir into the chamber to displace the space occupied by the air therein, and a valve for controlling the rate of flow in the last named conduit whereby liquid from the container will be proportionately released.

3. In apparatus of the character described, comprising in combination, a container for liquid material, a discharge conduit leading therefrom, a vacuum chamber in communication with the space above liquid in the container, a reservoir, the chamber being adapted to receive a liquid from the reservoir to displace the space occupied by the air therein said chamber having a capacity greater than the material in the container, and means for controlling the rate of flow of liquid into the chamber whereby liquid from the container will be proportionately released.

4. An apparatus of the character described, comprising in combination, a container for material that is to be dispensed, a discharge conduit leading from the container near the bottom thereof, a receptacle, a reservoir positioned thereabove and adapted to hold liquid, the reservoir having an opening through which liquid may flow into the receptacle, a float controlled valve for regulating the flow from the reservoir into the receptacle so as to maintain a uniform level of liquid at all times in the receptacle, an air chamber at a lower level than the receptacle, there being a passageway for liquid to flow from the receptacle to the chamber, a valve for controlling the last named flow, and means for providing communication between the air chamber and the space in the container above the liquid.

5. In a device of the character described, the combination of a container for holding liquid, a discharge conduit leading from the container so that liquid may flow by gravity therefrom, means for controlling the rate of flow, said means comprising a member having a lower air compartment, an intermediate liquid compartment, and a surmounting reservoir, there being a passageway between the reservoir and the intermediate compartment, and another passageway from the intermediate compartment to the air compartment, means for adjusting the rate of flow from the intermediate compartment to the air compartment and means for maintaining a uniform head of liquid in the intermediate compartment.

6. A method of dispensing material, drop by drop, for medication or feeding purposes, comprising utilizing above the material a partial vacuum, which normally prevents the flow of material, modifying the volume of air under said vacuum, by utilizing a drop-by-drop flow of liquid other than the material in said partial vacuum,

whereby the material is caused to flow drop-by-drop in substantially volumetric equality with the flow of liquid.

7. An apparatus for dispensing material, comprising a container for material, a discharge conduit leading therefrom, means for maintaining a partial vacuum in the space above the material in the container, so as normally to prevent the flow of material therefrom, a second container in communication with the space in the first container and means for modifying the volume of air under said vacuum by admitting a liquid into the second container, drop by drop, whereby the discharge of material from the first container is substantially identical to the flow of liquid into the second container.

8. An apparatus for dispensing liquid material, drop by drop, for medication or feeding purposes, comprising in combination, a container for storing the material, a discharge conduit leading therefrom, means for maintaining an air-tight seal within the container so as normally to prevent the flow of material therefrom, an air-tight compartment in communication with the container and means for flowing liquid drop by drop into the compartment, whereby the discharge of material from the first container is substantially identical to the flow of liquid into the second container.

9. An apparatus of the character described, comprising in combination a container for liquid material, a discharge conduit extending downwardly into the container and having the entrance thereto below the level of liquid therein and having the discharge end thereof positioned below the entrance end, a second container in communication with the first container above the level of the liquid therein, and means for maintaining a partial vacuum in the space above the material in the first container so as normally to prevent the flow of material therefrom, and means for flowing liquid drop by drop into the second container whereby the discharge of material from the first container is substantially identical to the flow of liquid into the second container.

10. A device of the character described, comprising in combination, two containers, each having a stopper, one of the containers having liquid therein and having a conduit extending through the stopper for conveying material therefrom, the entrance to the conduit being below the level of the liquid therein, and the other container having a conduit extending through the stopper for introducing liquid thereinto, there being a third conduit having its ends projecting through the respective stoppers, means for maintaining a partial vacuum within the two containers so as normally to prevent the flow of liquid from one of the containers and means for admitting a liquid into the other container drop by drop whereby the discharge of liquid from the first container is substantially identical to the flow of liquid into the other container.
